UNITED STATES PATENT OFFICE

155,587

DESIGN FOR A COMBINATION DIRECTIONAL SIGNAL AND BACKUP LIGHT

Henry G. Dibelka, Chicago, Ill., assignor to Auto
Lamp Manufacturing Co., Chicago, Ill., a lim-
ited partnership

Application April 1, 1949, Serial No. 1,758

Term of patent 14 years

(Cl. D72—1)

To all whom it may concern:

Be it known that I, Henry G. Dibelka, a citizen of the United States and a resident of Chicago, Cook County, Illinois, have invented a new, original and ornamental Design for Combination Directional Signal and Back-Up Light, of which the following is a specification, reference being had to the accompanying drawing, forming part thereof, in which

Fig. 1 is a perspective view of my new design for a combination directional signal and back-up light;

Fig. 2 is a plan view;

Fig. 3 is a rear elevation;

Fig. 4 is a side elevation; and,

Fig. 5 is a bottom plan view.

The dotted lines shown in the drawing are for illustrative purposes only.

I claim:

The ornamental design for a combination directional signal and back-up light, substan-
tially as shown and described.

HENRY G. DIBELKA.
